By E. C. Srooman Esq.,
Atty Attorney S.

UNITED STATES PATENT OFFICE.

WILLIAM H. CURL, OF FAIR PLAY, MISSOURI.

GRAVEL LOADER.

Application filed October 7, 1922. Serial No. 593,010.

To all whom it may concern:

Be it known that I, WILLIAM H. CURL, a citizen of the United States, residing at Fair Play, in the county of Polk and State of Missouri, have invented certain new and useful Improvements in Gravel Loaders, of which the following is a specification, reference being had therein to the accompanying drawings.

10 This invention relates to a gravel loader, and the object of the invention is the construction of a simple and efficient loader which can be easily assembled, or disassembled, thereby facilitating the handling or 15 transportation of the same.

Another object of the invention is the construction of a gravel loader which will allow a wagon or truck to pass under the same and be filled, and which also facilitates the 20 filling or loading of a vehicle by reason of allowing a loading vehicle to pass up and approach an inclined section onto a central section and then dumped through the central section into the vehicle to be loaded.

25 With these and other objects in view, my invention comprises certain novel combinations, constructions and arrangements of parts as will be hereinafter described, illustrated in the accompanying drawings, and 30 more particularly pointed out in the appended claims.

In the drawings:

Figure 1 is a view, in side elevation, of an apparatus constructed in accordance with 35 the present invention, while

Figure 2 is a top plan view of the same.

Figure 3 is an end view, in elevation, of the central section.

Figure 4 is a plan view of the floor frame 40 of the central section, while

Figure 5 is an end view of the same.

Figure 6 is a perspective view of one of the sections of the floor of the central frame.

Figure 7 is a perspective view of one of 45 the sections of the floor of the approach sections.

Figure 8 is a bottom plan view of the floor frame of the approach sections, while

Figure 9 is a view, in side elevation, of the 50 same.

Figure 10 is a view, in elevation, of one of the brace devices.

Figure 11 is a perspective view of an auxiliary standard of the approach section.

Figure 12 is a sectional view, taken on line 55 12—12, Fig. 1, and looking in the direction of the arrows.

Referring to the drawings by numerals, 1 designates the central section, and 2 are the two approach sections assembled there- 60 with.

The central section comprises vertical standards 3, and the two standards at each end of the central section are connected by a horizontal beam 4 (Fig. 3) upon which 65 beams 4 rest the beams 5 of the floor frame 6 (Fig. 4). Fastened to the top of beams 5 is a floor-structure 7 that is provided with a central opening 8 through which the gravel, or any suitable material, is dumped 70 into a waiting vehicle, such as a wagon or truck standing in the space A, Fig. 1. Resting upon beams 5, at opposite sides to the central floor-structure 7, are sections 9, Fig. 6. Attached to the inner faces of the outer 75 beams 5 are eye-bolts 10 for the purpose hereinafter described. Each beam 5 has its ends notched at 11 so that the floor-structure may be seated securely upon the end beams 4, Fig. 11.

In constructing my apparatus I employ two approach sections 2, but it will only be necessary for me to specifically describe one approach section, for the two are duplicates. The approach section 2 comprises floor 80 beams 12, each of which has its outer or lower end beveled, at 13, to rest snugly upon the ground (Fig. 1), and the upper end 14 of each beam 12 is cut at an angle to allow it to fit against the floor of the central section 1, and the beam is also provided with a notch 15, which allows the upper edge 15, Fig. 9, to rest snugly upon the beam 4. A rod 17 extends entirely across the floor beams 12, and on this rod 17 are a pair of comparatively long hooks 18. These hooks extend under the floor sections 9, and their outer ends are placed in the eye-bolts 10 (shown in dotted lines, Fig. 1), whereby the approach sections are attached to the central 95 100

sections. Each approach section is provided with cross bracing rods 19, to strengthen the same.

Brace devices 20 are used to assist in fastening the approach sections to the central section, each brace device comprising rod sections 21 and 22 connected by a turn buckle 23. The hook end 24 is connected to a chain 25, which chain is fastened at one end to the central section. The eye end 26 of section 22 is fastened to an approach section. It will be noted that these brace devices can be quickly assembled, and by reason of the turn buckle 23, tightened to a nicety.

I provide on each approach section a pair of railings 27, each railing 27 being detachably supported upon the upper ends of primary standard 28 and auxiliary standard 29. A strip 30 is secured across the end of the central standard, and upstanding pins 31 are carried by the strip, and the inner, upper end of each railing 27 is seated on the pin 31, Fig. 1; the railing 27^a of the central section is likewise secured in place.

On the sides of the outer floor beams 12 are primary angle brackets 32, and fastened to each standard (28 and 29) is an auxiliary angle bracket 33, which rests upon the top edge of the angle bracket 32, Figs. 1 and 12. By reason of this peculiar structure, the standards 28 and 29 can be quickly placed in position upon the approach section, or can be quickly disassembled, by merely moving the standard bodily, for a short distance, until the standard and bracket 33 clears the bracket 32.

The floor of the approach section includes a plurality of sections 34, Figs. 1 and 7. By reason of making the floor of approach sections in sections, as shown in Fig. 7, the floor can be more readily hauled about, and by reason of its sectional structure, can be easily handled by one operator.

It is to be noted that each railing 27 is seated between two plates 35 fastened to the upper end of each standard (28 and 29); this (plates 35) structure constitutes a bifurcated structure in which the railings 27 are detachably mounted, as shown in Fig. 1.

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

What I claim is:

1. In an apparatus of the class described, the combination of a central section provided with end beams, a pair of approach

sections assembled with said central section, 65 each approach section including a plurality of floor beams, each floor beam having its upper end cut at an angle and provided with a notch contiguous to the upper end, said notch provided with an upper edge resting 70 snugly upon a beam of the central section, a rod extending across all of said floor beams, a plurality of hooks on said rod and having their outer ends fastened to the central section, and a floor upon the floor beams. 75

2. In an apparatus of the class described, the combination of a central section provided with standards and with beams supported upon said standards, a pair of approach sections assembled with said central 80 section, each approach section provided with floor beams, each floor beam provided with a notch portion resting upon a beam of the central section, some of the beams of the central section provided with eye-bolts, hooks 85 pivotally mounted on the floor beams of the approach section and engaging said eye-bolts and a floor on the floor beams of the approach section.

3. In an apparatus of the class described, 90 the combination of a central section provided with beams, of approach sections assembled with said central section, each approach section comprising floor beams, each floor beam provided with a lower beveled 95 end and with an upper beveled end, each floor beam provided with a notch on its lower edge contiguous to the upper beveled end, the notched portion of the floor beam resting upon a beam of the central section, a floor 100 on the central section and having a portion engaging the beveled upper end of the floor beam, a rod extending through all of the floor beams of an approach section, hooks between some of the floor beams and pivotally mounted on said rod, eye-bolts on the 105 inner faces of some of said beams of the central section, said hooks engaging said eye-bolts, and a floor on said floor beams.

4. In an apparatus of the class described, 110 the combination of a central section, approach sections secured to said central section, standards secured to each approach section, plates secured to said central section, upstanding pins on said plates, and railings 115 detachably mounted on said standards and having their upper ends seated on said pins.

5. In an apparatus of the class described, the combination of a central section, approach sections secured to said central section, 120 each approach section provided on its sides with angle brackets, standards detachably positioned under said angle brackets, and angle brackets secured to said standards and engaging the top edge of the first-mentioned angle brackets.

6. In an apparatus of the class described, the combination of a central section, ap-

proach sections detachably secured at opposite sides to said central section, each approach section including standards at its sides, angle brackets provided with outer

5 open ends secured to the approach sections and overhanging the standards, angle brackets secured to the standards and bearing against the first-mentioned angle brackets,

and detachable railings mounted upon the upper ends of said standards and being detachably fastened at their upper ends to said central section. 10

In testimony whereof I hereunto affix my signature.

WILLIAM H. CURL.
